CLAIM

The ornamental design for a card holder for phone as shown and described.

DESCRIPTION

FIG. 1 is a perspective view of a card holder for phone showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 shows the card holder for phone in an environmental use of state;

FIG. 10 shows the card holder for phone in an alternative position in its environmental use state; and,

FIG. 11 shows an enlarged view of a portion of the card holder for phone from FIG. 2.

The broken lines in the drawings depict portions of the card holder for phone, and environmental subject matter that form no part of the claimed design.
